PATRICK EDWARD CUNNINGHAM AND REGINALD REID, OF CHIDLLOWS WELL, WESTERN AUSTRALIA, AUSTRALIA, ASSIGNEES OF ONE-HALF TO VALENTINE MURE FITZ-HUGH, OF DOODLAKIN, AUSTRALIA.

SPARK-ARRESTER FOR LOCOMOTIVES.

1,028,683.

Specification of Letters Patent.

Patented June 4, 1912.

Application filed June 30, 1911. Serial No. 636,207.

To all whom it may concern:

Be it known that we, PATRICK EDWARD CUNNINGHAM and REGINALD REID, both subjects of the King of Great Britain, and residing at Chidlows Well, Western Australia, Commonwealth of Australia, have invented certain new and useful Improvements in Spark-Arresters for Locomotives, of which the following is a specification.

10 This spark arrester for locomotives and other steam boilers essentially consists in the use of rotatable fans or bladed wheels which are so arranged and adapted as to be driven by the action of the exhaust steam. 15 The said fans rotate horizontally upon their axes and thus work in a vertical plane. These fans are so arranged that their bladed peripheries overlap and on each side are provided with gearing which governs and 20 controls their accurate working with each other as in true companionship.

Our invention will now be explained by the aid of the attached drawings in which—

Figure 1 is a front elevation of our arrester 25 as fitted to the funnel of the smoke box while Fig. 2 is a plan view of same. Figs. 3 and 4 are enlarged detail plan and side views respectively of the fan construction and part broken away as shown. Fig. 5 is 30 a fragmentary sectional view showing one of the devices for detachably connecting the blades to the cheek plates.

In said drawing *a* are the rotary companion fans or solid bladed wheels keyed on 35 their spindles *b* and built in and arranged within the outer funnel *c* and so set and adjusted that their peripheries overlap as shown and the respective blades work inter gear wise with each other. These fan blades 40 on their one face as shown carry outstanding or projectional plates *a*¹ whose duty is during the rotation of the fans to better deflect and catch the up flowing sparks. The fan blades are built removably on their 45 shafts and are held transversely between two end or cheek plates *a*² and these plates are of a lesser diameter than the blades and thus allow the latter to overlap with each other as shown. The ends of the fans are therefore closed except for those spaces which 50 exist between the peripheral edges of the blades *a* and the end plates *a*². The fan blades by preference are removably secured to the end cheek plates *a*² for purpose of the

fans being easily cleaned and brushed and 55 said plates are made with radial grooves or channels as *d* in which the blades are held and are provided with spring tongues as *d*¹ on their end edges and said tongues nest into suitable pockets *d*² in the cheek 60 plates and thus hold the fan blades securely in position. The shafts of these companion fans are operatively connected together at each side as shown in Fig. 2 by the transverse shafts *e* having bevel gears *f* which 65 mesh with the pinions *g* on the fan shafts *b*. By means of this bevel gearing the fans are maintained in true and uniform working 70 companionship. The fans are arranged immediately above the mouth of the inner 75 funnel *h* while a spark catchment chamber as *j* is continued downward and around the smoke box *k* as shown in Fig. 1. This chamber *j* is provided with a flap door *m* through which the dead sparks are removed.

The exhaust steam pipe is denoted by the letter *n*.

The working of our arrester is mainly as follows:—The exhaust steam upon issuing from the pipe *n* strikes against the fan blades 80 thereby rotating said fans *a* with the result that these fans act as live and moving barriers against the escape of the live sparks through the mouth of the funnel *h* and said 85 sparks are deflected and returned into the smoke box *k* or into the spark catchment chamber *j* and removed through the door *m*. The overlap of the fans combined with their closed ends prevents any sparks from escap- 90 ing up through the outer funnel *c*.

What we claim as our invention and desire to secure by Letters Patent is:—

1. A spark arrester comprising, in combination, a casing, a pair of co-operatively arranged revoluble spark-arresting members therein having blades, the blades of one member interengaging with the blades of the opposed member, an operative connection between said members for insuring rotation thereof in predetermined relation, and 95 a funnel contained in said casing for directing exhaust steam and products of combustion only against the interengaging blades of said members, said funnel forming spark-collecting chambers at opposite sides thereof 100 and directly beneath the outer peripheral portions of said bladed spark-arresting members.

2. A spark arrester comprising, in combination, a casing, a pair of coöperatively arranged revoluble spark-arresting members therein having blades, the blades of one member interengaging with the blades of the opposed member, means for causing rotation of the bladed spark-arresting members to maintain a predetermined relation between the interengaging blades thereof, and a funnel for projecting exhaust steam and products of combustion against the interengaging blades of said members, the outlet of said funnel having its walls arranged below and within the space between the axes of

said members, spark-receiving chambers being formed within the casing and exteriorly of said funnel, said chambers being directly below the outer peripheral portions of said members. 15

In testimony whereof we have hereunto set our hands in presence of two subscribing witnesses. 20

PATRICK EDWARD CUNNINGHAM.
REGINALD REID.
